DESIGN FOR A CASKET DISPLAY CANOPY

Clara W. Arnold, East Cleveland, and Oscar J. Hinger, Cleveland, Ohio

Application October 22, 1940, Serial No. 96,060

Term of patent 7 years

To all whom it may concern:

Be it known that we, Clara W. Arnold and Oscar J. Hinger, citizens of the United States, residing, respectively, at East Cleveland, in the county of Cuyahoga and State of Ohio, and at Cleveland, in the county of Cuyahoga and State of Ohio, have invented a new, original, and ornamental Design for a Casket Display Canopy, of which the following is a specification, reference being had to the accompanying drawing, forming part thereof.

We claim:

The ornamental design for a casket display canopy, substantially as shown.

CLARA W. ARNOLD.
OSCAR J. HINGER.
